UNITED STATES PATENT OFFICE.

ALBERT JAMES, OF EUREKA, CALIFORNIA.

SUBMARINE TRACTOR.

1,301,566.

Specification of Letters Patent. Patented Apr. 22, 1919.

Application filed June 7, 1917. Serial No. 173,412.

To all whom it may concern:

Be it known that I, ALBERT JAMES, a citizen of the United States, residing at Eureka, in the county of Humboldt and State of California, have invented new and useful Improvements in Submarine Tractors, of which the following is a specification.

This invention relates to a submarine tractor.

10 One of the objects of the present invention is to provide a simple, substantial, under-sea tractor designed to travel on the bottom of the sea and capable of withstanding high external pressure. Another object 15 of the invention is to provide grousers of the self-laying track type to support and propel the tractor and to permit it to travel over a bottom otherwise traversed with great difficulty and, furthermore, to form flukes 20 on each grouser capable of gripping the bottom, thereby increasing the pull or tractive force and also insuring greater stability. Further objects will hereinafter appear.

The invention consists of the parts and 25 the construction and combination of parts as hereinafter more fully described and claimed, having reference to the accompanying drawings, in which—

Figure 1 is a side elevation of the tractor. 30 Fig. 2 is a plan view of same, partly broken away.

Referring to the drawings in detail, A indicates a hull suitably wrapped and sheeted with steel of sufficient thickness and strength 35 to withstand comparatively high exterior water pressure, and at the same time being of sufficient size to accommodate an operator and a number of passengers, if desired. The hull is otherwise provided with a conning tower 2, a manhole 3 and a periscope 4 of standard construction, which may be elevated so that the operator can observe the surrounding surface conditions, when necessary. The hull proper is in this instance supported by a pair of tractors of the self-laying track type. These tractors are 40 independently driven by shafts 5 and 6, respectively, extending through stuffing boxes in the sides of the hull, and each shaft 45 is provided with a driving sprocket 7 over which the endless track passes and is propelled, the remaining portion of the track being supported upon a front idler 8 and intermediate supporting idlers 9.

50 Each tractor may be resiliently mounted, if desired, but as the particular construc-

tion and mounting of the tractors do not form any important feature of the present invention, I wish it understood that variations in the construction may be made without departing from the spirit of the invention. 60

Turnably mounted on each driving shaft, within the hull, is a large driving gear 8 which is directly driven from an electric 65 motor 9 through pinions 10, and formed interiorly of each gear is a cone face which is adapted to coöperate with a cone clutch 11 keyed but slidably mounted upon the shaft, there being one cone clutch on each 70 shaft. Each independent driving shaft is otherwise supported in suitable bearings, such as shown at 12 and 13, and they may, therefore, be driven in unison or independently of each other. The current supply for 75 the motor may be secured from two different sources, for instance, a suitable quantity of storage batteries may be carried within the hull or an insulated trailing cable 14 may be employed through which the current 80 passes.

The under-sea tractor constructed as here shown may be employed for a great variety of purposes. It may, for instance, be carried upon a ship and under such conditions 85 will be provided with two or more ring bolts, as shown at 16, to permit it to be lifted by means of derricks over the side and then lowered to the bottom of the sea. If the ship carrying the tractor is equipped with 90 electric generators, it is obvious that a trailing cable 14, such as shown, may be provided, thus permitting the current for the driving motor 9 to be supplied directly from the ship. The tractor thus propelled may be 95 directed shoreward, if the vessel is stranded to land life lines or cables over which breeches buoys may operate, or, if the ship has not struck with sufficient force when the tide is rising, it will in some instances be 100 possible to attach a towing cable to the tractor which may then be directed seaward to haul the ship off.

The tractor may also be used for the purpose of conveying people to and from a 105 stranded ship, and it may also be employed for mine laying in times of war and for discharging explosive bombs, torpedoes, and the like. It may also be used for general exploration of the sea bottom for the purpose 110 of mapping, laying contours, and many other purposes and may also be used in connection

with the salvaging of wrecks, particularly such as are sunk in comparatively deep water.

In traveling over the sea bottom, it can readily be seen that one operator alone can easily handle and steer the tractor. For instance, if it is desired to turn or steer the same it will only be necessary to throw out one clutch while the other is driving. This will permit one endless track to run idle while the other is driving. This permits it to turn any distance desired or in any direction, and as the motor employed is reversible, it is obvious that it can be reversed when necessary. The placing of the driving machinery in the bottom of the hull, together with the storage batteries and the like and also the positioning of the endless tractors below on each side of the hull, gives the tractor great stability.

The flukes, shown at 17, are preferably secured to the grousers of the tracks to increase the tractive force or pull particularly when a sandy bottom formation is encountered. This is of considerable importance where a vessel strands on a sandy beach, as the pull thus presented may often prove sufficient to release the vessel.

Formed in the rear end of the hull is a chamber 18 which is separated from the main interior by a bulk-head 19. Extending through the chamber and journals formed in each side is a shaft 20, which carries a pair of trailing spuds 21. These spuds may be raised or lowered with relation to the bottom by means of a worm gear 22 secured on the shaft which is operated from the main chamber by a hand-crank 23 and a shaft 24. This shaft passes through a stuffing box in the bulk-head as the chamber 18 may be filled with water.

The provision of the trailing spuds 21 is of great importance where the tractor is used as a crawling anchor. For instance, after leaving a ship and proceeding a certain distance it is possible to drop the spuds and reverse the tractor so as to force the spuds thoroughly in the bottom. The ship may then haul on the attached cable by means of its own winches or capstan and an

enormously greater pull can in this manner be exerted than when the tractor is held to the bottom by the flukes 17 only. A winding drum 25 may also be provided which is driven through the gears 26 from a motor 27. 55 This drum may carry the power cable and also a pulling cable, if desired, in this manner permitting the cables to be paid out or rewound as the tractor is traveling.

While a single driving motor is here 60 shown, it is obvious that two may be employed, one for each shaft. This may in some instances be preferable as it will eliminate the use of clutches. Other changes may also be made in the construction 65 throughout and such attachments, as compressed air tanks, from which air is automatically released to supply the operator and passengers, may also be employed although not specifically shown. 70

The materials and finish of the several parts of the machine are such as the experience and judgment of the manufacturer may dictate.

Having thus described my invention, what 75 I claim and desire to secure by Letters Patent is—

1. A submarine tractor comprising an enclosed hull, tractors supporting the hull, means for driving the tractors, a winding 80 drum within the hull supporting a cable, and means for driving the drum to pay out or pull in the cable.

2. A submarine tractor comprising an enclosed hull, tractors supporting the hull, 85 means for driving said tractors, spuds or flukes carried by the tractor adapted to be lowered to anchor the tractor to permit the tractor to be used as a crawling anchor, means for carrying a hawser to be attached 90 to a ship, and means for paying out or hauling in on the hawser when the tractor is operating.

In testimony whereof I have hereunto set my hand in the presence of two subscribing 95 witnesses.

ALBERT JAMES.
